UNITED STATES PATENT OFFICE

HORACE DRUMMOND BLACK, OF LONDON, ENGLAND, ASSIGNOR TO THE BELL PUNCH & PRINTING CO. LTD., OF UXBRIDGE, MIDDLESEX, ENGLAND

INKING APPARATUS OF PRINTING MACHINES

Original application filed November 26, 1927, Serial No. 235,877, and in Great Britain December 10, 1926.
Divided and this application filed October 24, 1928. Serial No. 314,817.

This invention relates to improvements in the inking apparatus of printing machines such as combined ticket printing and issuing machines, of the kind described in the specification of my application for a patent, Serial No. 235,877 of which this case is a division, in which the inking roller and the ink-duct roller, the former being formed of, or coated with, the usual resilient composition and both being of comparatively short length, are arranged in such a manner that they contact obliquely with one another, the effect of this oblique contact giving to the inking roller a somewhat similar ink distribution to that obtained with the lateral oscillating roller in the ordinary form of inking train.

In my said specification, the inking roller is carried on a pivot beneath the fixed revolving ink-duct roller, the consequent pivoting movement of the said inking roller to bring it into contact with the platen or printing cylinder being controlled by a cam, secured to the shaft of the said platen or printing cylinder, and rotating therewith, which operates one end of a bell-crank lever, the free end of the inking roller shaft being carried in a slot provided in the other end of the said bell-crank lever.

According to the present invention, the inking roller is arranged in continuous contact with the printing cylinder and the ink-duct roller, the latter being mounted obliquely relative to the inking roller.

In order that the invention may be fully understood I will now describe it by reference to the accompanying drawing, in which:

Figure 1 is a sectional elevation illustrating the improvements in accordance with the invention.

Figure 2 is a plan view thereof.

a is the ink-duct roller, revolving on the spindle *b*, and *c* is the ink-duct. *d* is the inking roller which revolves on the spindle *e*, and *g* is the printing cylinder mounted on the spindle *h*, the three spindles *b*, *e* and *h* being mounted in the framing *i*. The said inking roller *d* is arranged between the printing cylinder *g* and the ink-duct roller *a*, the latter being arranged obliquely with respect to the said inking roller. By this oblique

arrangement of the ink-duct roller *a*, it will be understood that the ink from the ink-duct *c* will be distributed on the inking roller *d* in a manner similar to that described in my specification hereinbefore referred to and transferred by the latter roller to the printing cylinder.

Claim:

An inking device for the printing cylinder of a printing machine, comprising an inking roller having a resilient surface, an ink-duct, and an ink-duct roller in permanent contact with the said inking roller but arranged obliquely thereto, the said inking roller being also arranged in permanent contact with the printing cylinder.

HORACE DRUMMOND BLACK.
